Primary Examiner—Catherine R Oliver(74) *Attorney, Agent, or Firm*—Jeffer Mangels Butler & Marmaro LLP(57) **CLAIM**

The ornamental design for a fishing jig, as shown and described.

DESCRIPTION

FIG. 1 is a perspective view of the fishing jig in accordance with an embodiment of the present invention;

FIG. 2 is a front elevational view of the fishing jig of FIG. 1, FIG. 3 is a left side elevational view of the fishing jig of FIG. 1;

FIG. 4 is a rear elevational view of the fishing jig of FIG. 1;

FIG. 5 is a top plan view of the fishing jig of FIG. 1;

FIG. 6 is a bottom plan view of the fishing jig of FIG. 1;

FIG. 7 is a perspective view of the fishing jig of FIG. 1 with the skirt and trailer removed; and,

FIG. 8 is a top plan view of the fishing jig of FIG. 1 with the skirt and trailer removed.

The broken line showing of environment in the drawings is included for the purpose of illustrating only and forms no part of the claimed design.
